SHOE SEWING MACHINE

Raymond L. Slinkard, Cape Girardeau, Mo., assignor to United Shoe Machinery Corporation, Flemington, N. J., a corporation of New Jersey

Application May 20, 1950; Serial No. 163,279

3 Claims. (Cl. 112—52)

1

The present invention relates primarily to improvements in shoe sole sewing machines and, more particularly to a sewing machine arranged to direct a crepe rubber wrapper strip having a tacky surface into a seam of a shoe.

Crepe rubber in shoe construction ordinarily is used with cement to attach the parts in place, the crepe rubber being applied by hand. Because of the tacky surfaces of crepe rubber, considerable difficulty has heretofore been experienced in leading such parts progressively into operative position in a sewing machine without manual assistance. Extremely thin parts, composed of crepe material are particularly difficult to control because of their great flexibility and to keep separate from other parts, before attachment because of their lively resiliency.

An object of the present invention is to provide a sewing machine with a guide for a tacky surfaced wrapper strip, which guide will be effective in directing the strip with an abrupt widthwise bend toward the point of operation of the machine, in such a way that obstruction of the work by reason of adhesive contact between the tacky surface on the strip and the guide is reduced to a minimum. Another object is to improve machine operations for attaching a crepe rubber strip to a shoe in a particularly desirable manner with the border of the crepe rubber strip brought progressively into accurate register with the line of the shoe.

In accordance with the above noted and other objects, the illustrated machine is arranged with a work clamping presser foot, a combined work support and guide formed with an open sided slot for receiving one border of a wrapper strip bent abruptly against the bulging upper of the shoe in angular relation with the other border, in which a retaining channel is provided within the slot for an enlargement along the border of the wrapper strip, the retaining channel acting to prevent adhesive contact between the wrapper strip and the surfaces of the slot in the guide and being provided with an overlying apron and an inclined gaging surface. To avoid obstruction through adhesive contact of the wrapper strip in the guide, the enlargement on the strip comprises a nontacky welt secured separately to the strip and so arranged relatively to the strip that when the welt is directed accurately into the seam line, the border of the wrapper strip automatically follows. With such arrangement if the inclination of the gaging surface is adjusted to induce widthwise squeezing action on the welt, the tendency is to press the wrapper strip firmly

2

against the bulge in the shoe upper, providing a desirable weather excluding construction.

To complete the shoe sewn on the machine a crepe rubber outsole is secured to the shoe with its edge face attached to the outer border of the wrapper strip.

These and other features of the invention as hereinafter described and claimed will be apparent from the following description taken in connection with the accompanying drawings, in which

Fig. 1 is a view in right side elevation and partly in section on an enlarged scale of those portions of a shoe sole sewing machine necessary to illustrate the features of the present invention;

Fig. 2 is a detail view in front elevation of the work support in the machine illustrated in Fig. 1 showing the position of a wrapper strip being directed into the point of operation of the machine;

Fig. 3 is a plan view of the work support;

Fig. 4 is a view in right side elevation of the work support;

Fig. 5 is a sectional view of a wrapper strip guide in the work support;

Fig. 6 is a perspective view of the wrapper strip and enlargement welt secured thereto before attachment to a shoe;

Fig. 7 is a sectional view of a shoe embodying the features of the present invention; and

Fig. 8 is a sectional view of a portion of a shoe constructed with a rectangular welt.

The illustrated machine is intended for operation on a stitchdown type of shoe in which an upper 8 is connected to an insole 10 by angularly disposed thread lasting stitches 12 passing through the marginal flange of the shoe which projects beyond the bulge of the upper. The stitches 12 form a thread lasting seam which is inserted while the upper and insole are supported on a last, indicated at 14. The machine is particularly intended for sewing a crepe rubber wrapper strip to the marginal flange of the shoe. Such wrapper strips ordinarily have extremely tacky surfaces so that adhesive contact between them and the surfaces of the machine parts or of the shoe before the point of attachment is reached tend to render it difficult, if not impossible, to guide or feed the strip accurately with relation to the line of sewing. Accordingly, it has been the practice with the use of a crepe rubber wrapper strip to attach one border of the strip temporarily to a shoe by a preliminary hand cementing operation. Thereafter, the exposed surfaces of the wrapper strip are covered with

a coating of powdered talc to allow them to slide more freely over the engaging and clamping surfaces of the sewing machine. In this way, the difficulty of positioning and guiding the tacky surfaced crepe wrapper strip during sewing is avoided and adhesive contact between the strip and the machine is substantially reduced.

The machine of the present invention also enables a crepe rubber wrapper strip 16 of relatively thin section to be directed into the point of operation of the machine in accurate relation to the line of the seam inserted by the machine without the necessity of preliminary hand cement attachment. The guiding action on the crepe rubber wrapper strip 16 is accomplished by the use of an enlargement along one border of the wrapper strip led into the machine with the strip. As shown in Fig. 6, this enlargement consists of a separate nontacky welt 18 secured by a seam 19 to the wrapper strip. The welt 18 is of rectangular cross-section with one edge along a corner having a bevel 20 at an angle of approximately 30° to the sides of the welt.

In directing the wrapper strip into the seam, the enlargement border of the strip passes through a combined work support and guide 21 having an open sided slot 22 inclined upwardly and forwardly toward the point of sewing operations in the machine. The open side of the slot 22 faces forwardly of the machine so that the wrapper strip extending from the slot is bent downward abruptly against the bulging upper of a shoe, the upper forcing the wrapper strip against the forward face of the work support. To prevent displacement of the wrapper strip and welt from the guide and to avoid adhesive contact between the strip and the guide, the guide has a retaining channel 24 formed by a rearward gaging surface 25 of the slot 22 inclined relatively to the seam line and a re-entrant lip 26 the edge of which extends into the slot of the guide and enters between the wrapper strip and the bevel 20 of the welt 18, the distance between the lip 26 and the rearward surface 25 of the slot being less than the width of the welt. The inclined surface 25 induces a widthwise squeezing action on the welt, tending to press the wrapper strip more firmly against the shoe upper as the shoe is fed in the machine. The lip 26 acts to hold the extreme edge of the wrapper strip from being raised from the channel during bending action against the bulging upper of the shoe and to retain the welt from displacement otherwise. The pressure of the upper against the wrapper strip in bending it is almost entirely exerted against the forward surface of the work support and does not obstruct movement of the wrapper strip sufficiently to interfere with the operation of the machine, the shoe upper moving with the wrapper strip to offset its tendency to adhere to the work support. Where necessary the operator of the machine may exert a slight widthwise tension on the strip to bring the level on the welt into firm guiding engagement with the lip 26.

As a means for preventing adhesive contact between the upper surface of the wrapper strip and the shoe before the sewing point is reached, the guide which is integral with the work support has a strip overlying apron 28 terminating at the clamping point of a presser foot 29 and the work support 21. The presser foot 29 acts on the margin of the shoe to clamp it both against the apron 28 before the sewing point is reached and against a raised shelf portion 30 of the work

support through which a needle receiving opening 32 passes beyond the sewing point. Thus the work is fixedly clamped at the sewing point with the shoe guided accurately through rearward pressure on the bent down wrapper strip, which in turn is directed by the forward surface of the work support. The wrapper strip and welt also are directed between the lip 26 beneath the apron 28 and the rearward face 25 of the slot 22 which is inclined forwardly and merges with the vertical shoulder behind the shelf 30, the slot face 25 being disposed at an angle to the seam line approaching the vertical shoulder of the shelf as the shoe is fed.

Besides the work support 21 and the presser foot 29, the sewing machine in which the invention is embodied comprises the usual curved hook needle 34, a curved awl 36, a shuttle 38, a locking thread case 40, a needle looper 42, a thread finger 44, and other devices similar to those disclosed in United States Letters Patent No. 1,169,909, granted February 1, 1916 upon application of Fred Ashworth. The machine is intended for operation upon shoe soles, the parts operated upon being clamped between the work support 21 and the presser foot 29 during stitch formation. After the completion of each stitch the parts operated upon are fed a stitch length by the awl 36 while engaging the work, the work being released from the clamping action of the presser foot at this time. Upon release of the work from the presser foot, the parts are raised slightly from the engaging surfaces of the work support so that adhesion between the crepe rubber wrapper strip and the work support is substantially avoided. Furthermore, the principle clamping pressure of the presser foot is transmitted downwardly upon the nontacky welt 18 which shields the work support in a large degree from contact with the tacky surfaced wrapper strip.

The bevel 20 on the welt 18 has two purposes, namely, to enable it and the wrapper strip border to which it is attached to be retained in the guide and to provide an improved shoe construction. After sewing the wrapper strip to the outflanked upper and insole, the margins of the upper and insole are trimmed to register with the welt and the unattached border of the wrapper strip is carried about the welt into lasted relation with the edges of the upper and insole. The welt 18 and its attaching stitches also are enclosed by the wrapper strip. To secure the wrapper strip in lasted over position, the shoe is completed with the attachment of a crepe rubber outsole 46 (see Fig. 7), all of the parts having been disposed with their edge surfaces in registry to provide a smooth surface over which the wrapper strip is lasted. The wrapper strip is brought into contact with the edge face of the outsole 46 and cemented thereto.

By reason of its accurate and uniform location the wrapper strip may be of such width that it reaches exactly to the lower tread surface of the outsole 46 and the thickness of the material from which the wrapper strip is composed may be much thinner than heretofore employed for similar purposes. The enlargement welt 18 provides an ample stitch retaining reinforcement to the sewed border of the wrapper strip and prevents expansion or distortion of the wrapper strip along its attached border during sewing operations.

With reference to Fig. 7 of the drawings it will be noted that the seam, indicated at 48, inserted by the machine, passes through the welt 18, one border of the wrapper strip 16, the outflanged

margin of the upper 8 and the insole 10. The upper threads of the stitches, however, are concealed by the folded over wrapper strip and the lower threads by the outsole 46. In this way a weatherproof construction is provided.

The nature and scope of the invention having been indicated and a particular embodiment having been described what is claimed is:

1. A shoe sewing machine for attaching a wrapper strip having a tacky surface to the marginal flange on a shoe projecting beyond the bulge of the upper, having a needle and a presser foot for clamping the work in sewing position, in combination with a work support provided with an integral confining guide for a nontacky welt, to one edge of which the wrapper strip is secured, an overlying apron on the work support terminating at the point of operation of the needle to prevent contact between the wrapper strip and the shoe flange until the sewing point is reached and a gaging surface on said guide inclined relatively to the seam line toward the shoe in the direction of work feed to induce widthwise squeezing action on the welt tending to press the wrapper strip against the bulge of the upper as the shoe is fed.

2. A sewing machine for attaching a wrapper strip having a tacky surface to the marginal flange on a shoe projecting beyond the bulge of the upper, having a needle and a presser foot for clamping the work in sewing position, in combination with a work support provided with an integral confining guide for a nontacky welt to one edge of which the wrapper strip is secured, an overlying apron on the work support terminating at the point of operation of the needle to prevent contact between the wrapper strip and the shoe flange until the sewing point is reached and a

re-entrant lip in the guide beneath the apron to enter between the wrapper strip and the welt to retain the welt from displacement.

3. A sewing machine for attaching a wrapper strip having a tacky surface to the marginal flange on a shoe projecting beyond the bulge of the upper, having a needle and a presser foot for clamping the work in sewing position, in combination with a work support provided with an integral confining guide for a nontacky welt to one edge of which the wrapper strip is secured, an overlying apron on the work support terminating at the point of operation of the needle to prevent contact between the wrapper strip and the shoe flange until the sewing point is reached and a re-entrant lip in the guide beneath the apron to enter between the wrapper strip and the welt to retain the welt from displacement, the wrapper strip projecting from the guide between the apron and a raised welt supporting shelf on the work support against which the work is clamped by the presser foot.
